UNITED STATES PATENT OFFICE.

JOHN SCHULDE, OF ST. LOUIS, MISSOURI, ASSIGNOR, BY MESNE ASSIGNMENTS, TO
HARRY L. HUSSMANN REFRIGERATOR & SUPPLY COMPANY, OF ST. LOUIS, MISSOURI, A CORPORATION OF MISSOURI.

SHOW-CASE REFRIGERATOR.

1,225,682.

Specification of Letters Patent.

Patented May 8, 1917.

Application filed August 21, 1915. Serial No. 46,686.

To all whom it may concern:

Be it known that I, JOHN SCHULDE, a citizen of the United States, and residing at St. Louis, in the State of Missouri, have invented 5 certain new and useful Improvements in Show-Case Refrigerators, of which the following is a specification.

This invention relates to refrigerators, being especially applicable to those of the display or show case type, which, heretofore, have involved an undue and, therefore, objectionable and expensive wastage of the cooling medium or refrigerant.

It is proposed to employ as a refrigerant 15 a mixture of cracked ice and salt, because of the known properties of such a mixture to produce, with a given amount of ice, a much lower temperature than could be obtained by the same amount of ice alone.

20 The invention has among its objects to remedy objectionable wastage of the refrigerant by providing an apparatus whereby the refrigerative medium is utilized to its fullest extent and a maximum of refrigeration, from a minimum of refrigerant, is obtained.

25 Further objects of the invention are to provide a comparatively simple, inexpensive refrigerator wherein a more thorough and 30 effectual chilling of the air, at the point of greatest refrigeration, is secured; a free circulation of the refrigerated air, throughout the entire display or refrigerator compartment, is maintained; and a practically continuous 35 cooling or chilling of the air, while being thus circulated, is effected.

Still further objects are to effectually control the circulatory course of the air through 40 the refrigerator compartment and to utilize the otherwise waste refrigerant for chilling the air while being thus circulated.

With these and other objects in view, the invention comprises the novel features of construction and combination of parts more 45 fully hereinafter described.

In the accompanying drawings;

Figure 1 is a side elevation of a refrigerator embodying the invention;

Fig. 2 is a top plan view of the same;

50 Fig. 3 is a vertical longitudinal section taken on the line 3—3 of Fig. 2;

Fig. 4 is a detail plan view of the drip

pan, auxiliary refrigerating pan, and drain trap, said parts being removed from the refrigerator;

55

Fig. 5 is a detail sectional view of the drain trap, the section being taken on line 5—5 of Fig. 4;

Fig. 6 is an enlarged vertical transverse section taken on the line 6—6 of Fig. 3; and, 60

Fig. 7 is a horizontal section through the refrigerating compartment, taken on the line 7—7 of Fig. 6.

In accordance with this invention, a refrigerating unit, comprising a freezing mixture container and a drip pan arranged below the container and receiving the brine therefrom, is arranged at one end of a show case compartment. This unit has passages constructed and arranged to permit a circulation of the air therethrough and along the back thereof, and the unit is adapted and positioned to cause a current of air to circulate in a path along the bottom of the show-case and in a return path along the top 70 of the show-case into the top of the unit.

Referring to the drawings, it will be seen that the refrigerator, which is designed upon the lines of a modern show or display case, comprises an oblong box or casing 1 having suitably insulated walls and subdivided, figuratively, into a refrigerating compartment 2, preferably located at one end of the casing, and a refrigerator compartment 3 coextensive with the remainder of the casing, there being set in the top wall of the latter a hinged lid or door 4 centered over the compartment 2, and a pair of fixed transparent panels 5 situated over the compartment 3, which is adapted to receive the goods to be shown or displayed, while set in one side wall of the casing is a pair of transparent panels similar to the panels 5 and in the other side wall a pair of hinged transparent doors or panels 6 disposed to afford 90 access therethrough to the interior of said compartment 3.

Removably sustained in the refrigerating compartment 2, to which ready access may be had through door 4, is a container 7 preferably formed of sheet metal and traversed fore and aft by a plurality of tapered tubular flues 8 constituting air passages opening at their larger ends through the front wall

of the container toward the compartment 3, and at their smaller or restricted ends into an air space or chamber 9, suitably formed at the rear end of the container and made common to all of the flues or passages 8. Under this construction there is imparted to the refrigerative body, consisting of the container and its contained refrigerant, a maximum surface area for a given cubic space, and, in consequence, there is offered to the air, which may circulate freely over and through this body, by way of passages 8 and chamber 9, a relatively large refrigerating surface by which a rapid absorption of heat from, and rapid and thorough refrigeration of, the air, is effected.

The bottom of the container is made in the form of a grate 10, consisting of a series of slats extending across and suitably attached to the lower end of the container, and serving to properly support the contained refrigerant 11, which latter preferably consists of a mixture of ice and salt. It has been found that when such a mixture is used and the container bottom simply perforated, as heretofore, there exists grave liability of such perforations becoming clogged and preventing proper escape of the water formed by the melting ice. This objection is overcome by providing the container with the grated bottom, of this invention, which permits free escape of the water.

Arranged in the compartment 2 beneath the container 7, to catch the drippings therefrom, is a sheet metal drip pan 12 adapted to overflow at its forward edge into the mouth 13 of a hollow overflow pan or duct 14 likewise made of sheet metal and, as will later appear, constituting a heat absorber, and, therefore, an auxiliary cooling medium for the compartment 3. The pan 14 is adapted to discharge at its forward end into a trap 15 having a drain pipe 16. The bottom of pan 12 is provided with transverse corrugations 17, and is pitched at a general forward and upward inclination, thus adapting it to accommodate and hold a quantity of the water, dripping from the container, before finally overflowing into the vertically disposed mouth of the overflow pan 14, which, in turn, is pitched at a general forward and downward inclination and is arranged to extend along the bottom of the casing 1 longitudinally through the compartment 3, and has its relatively spaced upper and lower walls provided with coincident corrugations 18, all for a purpose which will more fully hereinafter appear. The upper and lower corrugated plates of pan 14 are attached along their edges to, and connected by, side plates 18', which rest at their lower edges on the bottom of the casing for properly supporting the pan therein.

Attached at its upper edge to the front wall of the container, and at a point below

the uppermost flues or passages 8, is a vertically disposed insulated shield or baffle 19, preferably consisting of outer metal plates spaced apart to receive an insulating asbestos filling. This shield, from its point of attachment, extends outward and away from the container wall, and at a slight inclination downwardly and forwardly to provide an intervening air space or passage 20, while arranged to extend longitudinally of the compartment 3 is a horizontal, metal shelf 21, which terminates at its forward end short of the adjacent wall of said compartment, to provide an air pass 22, and at its rear end joins the lower edge of the baffle 19, and, thus, forms in effect, a continuation of the latter. The shelf 21 is disposed above, and in spaced relation to, the pan 14 to provide an air passage 23 directly over the latter, and is suitably sustained by side cleats or brackets 24.

Disposed in the compartment 3 suitably above the shelf 21 is a slatted or grate-like shelf 25, supported by brackets 26 and adapted to receive the goods to be displayed and refrigerated, and to permit free passage of the cold air therethrough for circulation over and around said goods.

In practice door 4 of compartment 2 may be opened and the container 7 filled with a suitable refrigerant, preferably such as described, and the goods to be preserved and displayed having been introduced into compartment 3, through the doors 6, and properly arrayed on the shelf 25; the doors are all properly closed and refrigeration begins. The warmer air within the casing naturally rises and travels rearwardly toward the refrigerative body, and as the two uppermost passages 8 open above the baffle 19, into the compartment 3, a current of air from the latter will flow through said passages and into the chamber 9. At this point it is to be noted that, because of the tapered flues having their larger ends disposed outwardly, a free passage of the air into and through these flues is induced, and further, that the air entering the flues becomes chilled and contracts, for delivery, in such contracted condition, through the smaller or restricted ends of the flues into the chamber 9, where it will undergo a further chilling and consequent contraction, and finally pass from said chamber into the other flues of the series and outward therethrough into space 20. During its outward passage, the chilled or refrigerated air, first enters the flues at their smaller ends in a highly contracted state, and will, therefore, as it flows through the now gradually widening passages, be relieved of compression and allowed to suddenly expand with a resultant lowering of its temperature, and as this air is now at the point of greatest refrigeration, it will be thoroughly and effectually chilled.

and rarefied. Upon escape from the passages 8 into the space 20, the refrigerated air is directed by the baffles 19 and 21 through the passage 23, to the air pass 22, 5 through which it passes into the refrigerator compartment 3, beneath the grated shelf 25, which, owing to its latticed formation, permits free circulation of the air around the goods, and final free return of the air to the 10 upper flues 8.

It is to be noted that the cooling or refrigerating action is effected wholly by a current of highly rarefied and chilled air traveling along and through the refrigerator 15 compartment, and that any moisture of condensation which might form in said compartment will be taken up and carried off by this air current and be deposited in the flues 8 and chamber 9 during the periods 20 of sudden chilling of the air within these parts, as before explained, and as will be obvious. The refrigerator compartment is thus kept dry and the deposit of moisture, bearing the odor or flavor of one food 25 article upon other food articles on the shelf, is prevented.

Attention is also directed to the fact that, owing to the shield 19 being insulated, as described, the highly chilled air issuing 30 from the flues 8 is deflected without chilling, by direct action, the air at the other side of said shield, within the compartment 3, and thus, the formation of eddy currents at this point in the compartment is prevented.

35 The absorption of heat by the refrigerant body from the air flowing through and around said body, causes melting of the refrigerant 11 and the water thus formed drips freely through the grate 10 into the underlying pan 12. As this water is, however, sufficiently cold to materially aid in the chilling or refrigeration of the air, the pan is constructed, as described, to accumulate and hold a quantity of this water as an 40 auxiliary refrigerative medium, disposed to act upon a current of air delivered from the lower end of chamber 9, while the overflow from the pan 12 is received by, and accumulates in, the pan 14, which is thus maintained 45 at a sufficiently low temperature to act as a heat absorbent and as a further refrigerative auxiliary for cooling the air within the compartment 3, it being noted that, inasmuch as the element 14 is disposed for direct 50 contact with the air current flowing through passage 23, it will act more particularly for maintaining the low temperature of said air current.

As a result of providing the pans 12 and 60 14 with the transverse corrugations 17 and 18, respectively, these elements are given a maximum surface area, are adapted to be more readily and effectually chilled under the action of the cold water, and the corrugations 18 may act as baffles for retarding 65

the current of cold air in its travel through the passage 23, thus to obtain its full effect in refrigerating the compartment 3.

It is apparent that, under this invention, there is produced an efficient refrigerator, 70 of the show case type, in which provision is made for a thorough utilization of the refrigerant, and by which the other stated objects are fully accomplished. In attaining these ends the invention is not necessarily 75 restricted to the details herein shown and described, and various minor changes may be made in such details without departing from the spirit or scope of the invention.

Having thus described the invention, what 80 is claimed is:

1. A counter refrigerator comprising an elongated show-case having transparent panels, a refrigerating unit including a container adapted to receive a freezing mixture 85 and mounted at one end of said show-case, said container having a vertical passage at the back thereof and having tubes passing therethrough and open at their rear ends to said vertical passage and at their forward ends to said show-case, constructed and arranged to permit a circulation of air through the unit and along the back thereof, and said unit being adapted and positioned to cause a current of air to circulate in a 90 path from the bottom of said unit along the bottom of said show-case and in a return path along the top of the show-case into the top of said unit.

2. A counter refrigerator comprising an 100 elongated show-case having transparent panels, a refrigerating unit including a container adapted to receive a freezing mixture and mounted at one end of said show-case, and a drip pan arranged below the container and receiving the brine therefrom, 105 said container having a vertical passage at the back thereof and having tubes passing therethrough and open at their rear ends to said vertical passage and at their forward ends to said show-case, constructed and arranged to permit a circulation of air through said unit and along the back thereof, and said unit being adapted and positioned to cause a current of air to circulate in a path from the bottom of said unit along the bottom of said show-case and in a return path along the top of the show-case into the top of said unit.

3. A counter refrigerator comprising an 120 elongated show-case provided with transparent panels, a refrigerating unit adapted to receive a freezing mixture and mounted at one end of said show-case, said unit having 125 passages constructed and arranged to permit a circulation of air therethrough and along the back thereof, and said unit being adapted and positioned to cause a current of air to circulate in a path from the bottom of said unit along the bottom of the show- 130

case and in a return path along the top of the show-case into the top of said unit, and a pan extending along the bottom of the show-case beyond said unit and adapted to receive the brine from said unit.

5 4. A counter refrigerator comprising an elongated show-case having transparent panels, a refrigerating unit adapted to receive a freezing mixture and mounted at 10 one end of said show case, said unit having passages constructed and arranged to permit a circulation of air therethrough and along the back thereof, and said unit being adapted and positioned to cause a current 15 of air to circulate in a path from the bottom of said unit along the bottom of the show-case and in a return path along the top of the show-case into the top of said unit, and a baffle positioned between the 20 inlet and outlet of said unit and adapted to direct said current of air.

25 5. A refrigerator comprising a casing having a refrigerator compartment and a compartment adapted to receive a refrigerative body, said body being provided with open ended passages each opening at one end toward said refrigerator compartment, the 30 said passages having their other ends terminating and adapted for communication with one another within said body, whereby the air being refrigerated will pass from one to another of said passages without leaving the said body.

35 6. A refrigerator comprising a casing having a refrigerator compartment and a compartment adapted to receive a refrigerative body, said body being provided with open ended tapered passages having their larger 40 ends disposed toward said refrigerator compartment and their smaller ends terminating, and adapted for communication with one another, within said body, whereby the air being refrigerated will pass from one to another of said passages without leaving the 45 said body.

50 7. A refrigerator comprising a casing having a refrigerator compartment and a compartment adapted to receive a refrigerative body, said body having a chamber inclosed 55 therein and being provided with a plurality of open ended tapered passages having their larger ends disposed toward said refrigerator compartment and their smaller ends opening into said chamber, whereby the air being refrigerated will pass within said chamber from one to another of said passages without leaving the said body.

60 8. A refrigerator comprising a casing having a refrigerator compartment, a container mounted in said casing and adapted to receive a refrigerant and constituting a refrigerative body, said container having a chamber inclosed therein and being provided with a plurality of open ended tapered 65 passages having their larger ends disposed to-

ward said compartment and their smaller ends opening into said chamber; whereby the air in said compartment is adapted to circulate through said body and to pass from one to another of said passages without leaving the said body at the inner ends of the 70 passages.

9 9. A refrigerator comprising a casing having a refrigerator compartment and a compartment adapted to receive a refrigerative body, said body being provided with open tapered passages having their larger ends disposed toward said refrigerator compartment and their smaller ends terminating, and adapted for communication with one 75 another, within said body; whereby the air being refrigerated will pass from one to another of said passages without leaving said body, and a baffle interposed between the forward ends of certain of said passages and 80 the refrigerator compartment.

10 10. A refrigerator comprising a casing having a refrigerator compartment, a refrigerant container disposed in said casing, said container having a chamber inclosed 90 therein and being provided with tapered open flues having their larger ends disposed toward said compartment and their smaller ends opening into said chamber for communication one with another within said 95 container.

11 11. In a refrigerator, a casing having a refrigerator compartment, a refrigerant container having a chamber inclosed therein and being provided with a plurality of fore and 100 aft open ended flues opening at their outer ends toward said compartment and at their inner ends into said chamber for communication one with another within said container, and an insulated baffle interposed between said compartment and the outer ends 105 of certain of said flues.

12 12. In a refrigerator a casing having a refrigerator compartment, a refrigerative body having a chamber and provided with 110 a tapered passage leading from said compartment through said body and opening at its smaller end into said chamber, said body having a second tapered passage leading therethrough and opening at its smaller end 115 into said chamber, and a baffle interposed between the larger end of said second passage and said refrigerator compartment.

13 13. In a refrigerator a casing having a refrigerator compartment, a refrigerative body having a chamber and provided with a tapered passage leading from said compartment through said body and opening at its smaller end into said chamber, said body having a second tapered passage leading therethrough and opening at its smaller 120 end into said chamber, and an insulated baffle interposed between the larger end of said second passage and said refrigerator compartment.

14. A refrigerator comprising an elongated show case provided with transparent panels, a refrigerant container mounted at one end of said case, said container having a chamber inclosed therein and being provided with a plurality of open ended tapered flues having their larger ends disposed toward said case and their smaller ends opening into said chamber for communication one with another within said container, an auxiliary heat absorbent body extending along the bottom of said show case, said body being fed and cooled by waste from said container, and a baffle interposed between said show case and the adjacent ends of certain of said flues, constructed and arranged to cause a current of air to circulate through said show case in a path along and immediately above said body.

15. A refrigerator comprising a show case

provided with transparent panels and having an end compartment adapted to receive a refrigerative body, said body being provided with upper and lower open ended tapered passages having their larger ends disposed toward said show case and their smaller ends terminating, and adapted for communication with one another, within said body, whereby air flowing into the upper passage will, without leaving said body, flow in a return path through said lower passage, and a baffle between the outer ends of said upper and lower passages, constructed and arranged to direct the return flow of air from said body in a path along, and adjacent the bottom of, said show case.

In testimony whereof I affix my signature this 7th day of August, 1915.

JOHN SCHULDE.
